US0D1037253S

(12) **United States Design Patent** (10) **Patent No.:** **US D1,037,253 S**
(45) **Date of Patent:** **** Jul. 30, 2024**

(54) **HANDHELD SCANNER**

(71) **Applicant:** **GuangZhou Netum Electronic Technology Co., Ltd.**, Guangdong (CN)

(72) **Inventor:** **Liwei Zeng**, Guangdong (CN)

(**) **Term:** **15 Years**

(21) **Appl. No.:** **29/820,089**

(22) **Filed:** **Dec. 20, 2021**

(51) **LOC (14) Cl.** **14-02**

(52) **U.S. Cl.**

USPC **D14/428**

(58) **Field of Classification Search**

(57) **CLAIM**

The ornamental design for a handheld scanner, as shown and described.

DESCRIPTION

FIG. 1 is a perspective view of a handheld scanner showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings illustrate the portions of the handheld scanner, which form no part of the claimed design.

1 Claim, 8 Drawing Sheets
